UNITED STATES PATENT OFFICE.

JEROME M. SCHWERIN, OF NEWARK, NEW JERSEY.

DESIGN FOR A CORNER-IRON FOR TRUNKS.

SPECIFICATION forming part of Design No. 24,214, dated April 16, 1895.

Application filed March 9, 1895. Serial No. 541,198. Term of patent 7 years.

To all whom it may concern:

Be it known that I, JEROME M. SCHWERIN, of Newark, in the county of Essex and State of New Jersey, have invented a certain new and useful Design for Trunk Corner-Irons; and I do hereby declare the following to be a full, clear, and exact description of the invention, such as will enable others skilled in the art to which it pertains to make and use it, reference being had to the accompanying drawings, which form part of this specification.

My invention relates to improvements in trunk corner irons, which are illustrated in the accompanying drawings forming part of this specification.

Figure 1 is a perspective view from the outer side of the trimming. Fig. 2 is a perspective view from the inner side of the trimming.

The leading features of my design relate to providing the angular corner A with a high

flange B at one side thereof and having a configuration on the outer side of this clasp consisting of an outwardly extending bulge D which extends down to the corner of the angle piece as shown, the upper end of the said bulge being tapered. At the rear side of the angle piece is another tapered bulge II, which extends to the lower end of the angle piece as shown, and coincides with the corner bulge D. 25 30

Having thus described my invention, what I claim, and desire to secure by Letters Patent, is—

The design for trunk corner irons, substantially as herein shown and described. 35

In testimony whereof I affix my signature in presence of two witnesses.

JEROME M. SCHWERIN.
